UNITED STATES PATENT OFFICE.

ROBERT T. HASLAM, OF BELMONT, MASSACHUSETTS, ASSIGNOR TO STANDARD DEVELOPMENT COMPANY, A CORPORATION OF DELAWARE.

FURNACE-WALL CONSTRUCTION.

Application filed August 16, 1923. Serial No. 657,827.

This invention relates to heating systems, and will be fully understood from the following description, taken in connection with the accompanying drawing, in which—

5 Fig. 1 is a vertical longitudinal section of a furnace and heating chamber embodying construction in accordance with the principles of the invention;

10 Fig. 2 is a sectional view, showing a detail of another form of construction contemplated; and

Fig. 3 is a cross section of another embodiment of the invention.

15 As is well known, the efficiency of heat take-up in furnaces in general is undesirably low and the limitations have been considered as quite effectual.

20 In accordance with the present invention, I am enabled to secure increased utilization of the heat available, and with relatively inexpensive construction in the refractories in the heating chamber, while also bringing to advantageous use the factor of radiation transfer.

25 Referring more particularly to Fig. 1 of the drawing, the reference character 1 designates a fire-box or furnace, and mounted in any suitable manner are shown tubes 2 to be heated. Such tubes may be those of 30 water-tube boilers, oil heaters, etc. At intervals along the chamber space are projections 3 extending from the walls so as to present a considerable exaggeration or redundancy of exposure, and additional virtual 35 extensions of radiating surface are effected by brick 4 or the like; these being in loose or open placement to allow free passage of the hot products of combustion and at the same time being located in radiating 40 relation to the tubes 2 or objects to be heated. Such exposures present a correspondingly increased means for taking up heat from gases beyond the zone wherein substantial combustion takes place and correspondingly function also to radiate it in 45 turn to the tubes or objects "in sight" which are to be heated.

50 Instead of tubes as illustrated, a shell boiler or the like, or solid objects for instance, may be similarly heated.

In the form shown in Fig. 2 a heating chamber or flue 10 carrying products of combustion or hot gases contains tubes 11 or other objects to be heated. In the path

of the hot gases and in radiating relation 55 with respect to the tubes 11 are heat-receiving and radiating exposures 12, connected with the wall or independent thereof if preferred, except as to necessary support, and placed in loose or open formation so 60 as to allow free passage of the hot gases.

In the form shown in Fig. 3 the object to be heated is another chamber; the chamber 20 for illustration being the heating side and the chamber 21 the side to be heated. 65

Examples of instances of such character are muffle furnaces, heating flues for gases and chemical products, flues for recuperative recovery of waste heat from hot waste gases for preheating air for furnaces, etc. The 70 projections 22 exposed to the hot gases take up heat and function in turn to radiate heat to the partition wall 23 which conducts the heat to the cooler gas in chamber 21. Additionally the wall 23 radiates heat to the exposures 24, and these in turn give up heat by conduction to the cooler gas in contact.

75 While most convenient as a matter of support, the elements 22 and 24 need not necessarily be attached to the walls. 80

The materials employed in construction of radiating elements according to the present invention may comprise the usual refractories. By reason of the increased efficiency resultant from this invention, however, relatively expensive materials, carborundum, the durable alloys of iron, etc., can be used 85 for conducting partitions, or the like, where such materials would not have been justified in the old practice. 90

In the constructions illustrated, it will be seen that heat is taken up by the exposed elements provided and these in turn as heat conversion transfer elements transfer the heat to the objects to be heated. 95

While I have described my invention by reference to certain details, it will be understood that this is for the purpose of illustration to make the invention clear, and is not limitative, and the invention is to be 100 considered as limited only as defined in the following claims, in which it is my intention to claim all inherent novelty as broadly as the prior art permits.

What I claim is:

1. In combination, a combustion zone, a heating chamber arranged to receive hot gases from said zone, refractory, redundant

exposures positioned in said chamber in effective heat-radiating relation to an object to be heated and beyond the region in which substantial combustion takes place, ~~6~~ said redundant exposures abstracting heat from the hot gases and radiating the same upon said object.

2. In combination, a fire box, a heating chamber into which hot gases from said fire box pass, refractory, redundant exposures in said chamber and positioned beyond the zone in which substantial combustion takes place, and a tubular body to be heated arranged adjacent said redundant exposures, whereby such exposures take up

heat from said hot gases and radiate the same upon the tubular body.

3. In combination, a fire box, a heating chamber into which hot gases from said fire box pass, refractory, redundant exposures projecting inwardly from the walls of the heating chamber beyond the zone in which substantial combustion takes place, and a plurality of tubes to be heated arranged in the heating chamber and adjacent said redundant exposures, whereby such exposures take up heat from the hot gases and radiate the same upon the tubes. ~~20~~ ~~25~~

ROBERT T. HASLAM.
